F. DUTCHER.
RAILWAY SIGNAL TORPEDO.
APPLICATION FILED JAN. 7, 1921.

1,414,264.

Patented Apr. 25, 1922.

UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

RAILWAY SIGNAL TORPEDO.

1,414,264.

Specification of Letters Patent. Patented Apr. 25, 1922.

Application filed January 7, 1921. Serial No. 435,645.

To all whom it may concern:

Be it known that I, FRANK DUTCHER, a citizen of the United States, residing at Versailles, in the county of Allegheny and State of Pennsylvania, have invented certain new and useful Improvements in Railway Signal Torpedoes, of which the following is a specification, reference being had therein to the accompanying drawing.

10 This invention relates to improvements in railway signal torpedoes, provided with rail-engaging members for fastening the torpedo to the rail head of a track.

The invention comprises a torpedo explosive charge wrapped in sheet fibre, or the like, and a rail-engaging member or strap which is fastened securely to the fibre wrapping.

The object of my invention is to provide 20 a torpedo of the railway explosive type, which is simple and cheap of manufacture.

A further object of my invention is to construct a torpedo of the explosive type in which the charge containing case is composed of paper or fibrous material wrapped around the charge and which will, to a great extent, lessen possible damage or injury by flying fragments when the charge is exploded.

30 Another object of my invention is to provide a simple and cheap manner by which a rail-engaging member or strap can be securely fastened to a torpedo to assure its being held firmly in place when put on a track to be struck and exploded by the wheel of a locomotive or car.

Other and further objects will appear in the following description and drawings, in which:—

40 Figure 1 is a perspective view of a torpedo embodying my invention.

Fig. 2 is a vertical sectional view through a torpedo having the embodiment of my invention.

45 Fig. 3 is a vertical sectional view taken on the line 3—3 of Fig. 2.

Fig. 4 is a perspective view of a torpedo embodying my invention, the parts being shown in extended positions before being 50 assembled.

Referring now to the drawings in which like parts are designated by similar ref-

erence numerals, 1 designates the explosive charge or tablet and 2 the wrapped fibrous sheet container or case therefor.

As clearly shown in Fig. 4, the explosive is wrapped within the sheet which encircles it with several folds, as shown at 3, and has oppositely extending portions 4 and 4'.

The preferable form of rail-engaging 60 member is a lead strap 5, but it will be readily understood that I do not limit myself to this particular means of track fastener, as light spring metal or its equivalents, suitable pliable material, or the like 65 can be readily adapted to this use.

Openings 6 are provided in the extending portions 4 and 4' of the case to receive the rail strap 5, which is threaded therethrough, as shown in Fig. 4, while these portions are 70 in their extended positions.

That portion of the strap 5 between the extended portions of the case is pushed down against the main case 2 and a fastening sheet 7 is adhesively, or otherwise suitably applied to the strap and case, to hold the strap in position.

The extended portions 4 and 4', which are preferably of a length to overlap, as shown at 8, are then folded inward upon the case 80 2 and the strap and its fastening and suitably fastened in this position.

By the foregoing steps the track-engaging member is securely fastened or locked to the torpedo.

It is well-known to those skilled in the art that the track-engaging member must be fastened securely to the torpedo so that when it is placed on a rail-head it will not be dislodged from the rail or separated from its rail-fastening when struck by a train wheel.

To further strengthen the fastening of the rail-engaging member 5 to the torpedo, a sealing wrapping 9, preferably of two-folds or thicknesses, is wrapped around the 90 torpedo case after the same has been folded as described.

If desired the completed torpedo may be given a water-proofing bath to assure that dampness will not penetrate the case to the 100 explosive charge and prevent its explosion when struck.

In the preferred embodiment of my invention, each of the extending wrapped por-

tions 4 and 4' is provided with openings 6 through which the rail-engaging member is threaded.

Having thus described my invention, what 5 I claim and desire to secure by Letters Patent is:—

1. A railway signal torpedo comprising an explosive and a case therefor having inwardly folded extended portions, a rail 10 engaging member passing longitudinally through one of said folded portions, and the extended portions adapted to overlap one upon the other so that the end of each lies adjacent the openings through the other.
- 15 2. A railway signal torpedo comprising an explosive and a case therefor, the case composed of a plurality of wraps of fibrous material having inwardly folded extended portions, and a rail-engaging member passing longitudinally through the several wraps of the extended inwardly folded portions, for the purpose described.
- 20 3. A railway signal torpedo comprising an explosive and a case therefor having inwardly folded extended portions, a rail-engaging member passing longitudinally through said folded extended portions intermediate their ends, a fastening for the rail-engaging member beneath the folded portions, whereby the rail-engaging member lies beneath only a portion of the length of the inwardly folded portions.
- 25 4. A railway signal torpedo comprising an explosive and a casing therefor having folded extended portions, a rail-engaging member passing through and beneath said folded extended portions, and a fastening for the rail member beneath the said folded portions.
- 30 40 5. A railway signal torpedo comprising

an explosive and a casing therefor having folded extended portions, a rail-engaging member passing through and beneath said folded portions, a fastening for the rail-engaging member beneath said folded portions, 45 and a wrapping embracing the said folded portions.

6. A torpedo comprising an explosive having a casing wrapped thereupon, the casing provided with extended wrapped portions 50 adapted to be folded inward, a rail-engaging member threaded longitudinally through suitable openings in the extended portions intermediate their ends, and the extended portions folded inward and overlapping one 55 another for the purpose described.

7. A railroad signal torpedo comprising an explosive and a casing therefor having folded extended portions, a rail-engaging member passing through and beneath one of 60 said folded portions, and a fastening beneath one of said folded portions.

8. A railway signal torpedo comprising an explosive and a casing therefor having folded extended portions, a rail-engaging 65 member passing through said folded extended portions intermediate their ends, and a fastening member for the rail-engaging member beneath the folded portions.

9. A railway signal torpedo, comprising 70 an explosive and a casing therefor having folded extended portions, a rail-engaging member passing through and beneath said folded portions, a fastening for the rail-engaging member beneath said folded portions, 75 and a wrapping transverse the folded portions and embracing them.

In testimony whereof I hereunto affix my signature.

FRANK DUTCHER.
